United States Patent Office

HUGH S. KERR, OF PHILADELPHIA, PENNSYLVANIA, ASSIGNOR TO ISRAEL FOSTER, OF SAME PLACE.

Design No. 4,652, dated February 14, 1871.

DESIGN FOR A CARPET-PATTERN.

The Schedule referred to in these Letters Patent and making part of the same.

I, HUGH S. KERR, of Philadelphia, county of Philadelphia, State of Pennsylvania, have invented or produced a Design for a Carpet-Pattern, of which the following is a specification.

The figure in the accompanying drawings represent sufficient of a carpet-pattern to illustrate my design, the remainder of the carpet-pattern being merely a petition of that which appears.

The main figures A of the pattern are each composed of four bars or ribbons, which interlock and cross each other at right angles in the manner clearly shown in the drawings; and the space between these figures is occupied by foliated ornamentation, B, arranged in diagonal stripes, which cross each other at right angles, the said stripes being enlarged at the points of crossing so as to form wreaths or borders, within which are contained spots or ornaments, C.

Irrespective of the colors employed,
I claim—

1. The design for the figures A, as shown and described.
2. The design for the foliated ornamentation B, as described and represented.
3. The design for the whole pattern, including the figures A, foliated ornamentation B, and spots C.

In testimony whereof I have signed my name to this specification in the presence of two subscribing witnesses.

HUGH S. KERR.
